US0D1020870S

(12) **United States Design Patent** (10) Patent No.: **US D1,020,870 S**
(45) Date of Patent: ** Apr. 2, 2024

(54) **DIGITAL MULTIFUNCTION DEVICE**

(71) Applicant: **FUJIFILM Corporation**, Tokyo (JP)

(72) Inventors: **Megumi Okubo**, Tokyo (JP);
Masahiko Yamamoto, Tokyo (JP)

(73) Assignee: **FUJIFILM CORPORATION**, Tokyo
(JP)

(**) Term: **15 Years**

(21) Appl. No.: **29/760,929**

(22) Filed: **Dec. 4, 2020**

(30) **Foreign Application Priority Data**

Jun. 4, 2020 (JP) 2020-011086

(57) **CLAIM**

The ornamental design for a digital multifunction device, as shown and described.

DESCRIPTION

FIG. 1 is a perspective view of a digital multifunction device showing our new design;

FIG. 2 is a front view of the digital multifunction device; FIG. 3 is a rear view of the digital multifunction device; FIG. 4 is a right view of the digital multifunction device; FIG. 5 is a left view of the digital multifunction device; FIG. 6 is a plan view of the digital multifunction device; and, FIG. 7 is a bottom view of the digital multifunction device. The part represented by solid line is the claimed design. The dash-dot broken lines in the drawings illustrate portions of the article that form no part of the claimed design. The dash-dot-dot broken lines represent the bounds of the claimed design and form no part of the claimed design.

1 Claim, 7 Drawing Sheets
